UNITED STATES PATENT OFFICE.

HARRY R. MEYER, OF PITTSBURGH, PENNSYLVANIA, ASSIGNOR TO WESTINGHOUSE ELECTRIC & MANUFACTURING COMPANY, A CORPORATION OF PENNSYLVANIA.

CIRCUIT-INTERRUPTER.

1,368,344.

Specification of Letters Patent. Patented Feb. 15, 1921.

Application filed October 7, 1916. Serial No. 124,281.

To all whom it may concern:

Be it known that I, HARRY R. MEYER, a citizen of the United States, and a resident of Pittsburgh, in the county of Allegheny and State of Pennsylvania, have invented 5 a new and useful Improvement in Circuit-Interrupters, of which the following is a specification.

My invention relates to circuit interrupters and particularly to interrupters of the railway or inclosed arc-extinguishing type.

One object of my invention is to provide 10 a circuit interrupter of the above-indicated character that shall be adapted to be tripped either automatically or by the movement of its operating handle.

Another object of my invention is to provide 15 an arc chute for an interrupter of the above-indicated character that shall be adapted to be removed from the inclosing housing of the interrupter without the necessity of opening the same.

A further object of my invention is to provide 20 a circuit interrupter of the above-indicated character that shall be compact in structure, cheap to manufacture, readily adjustable and reliable in its operation.

Figure 1 of the accompanying drawings 25 is a plan view, with the cover removed, of 30 a circuit interrupter embodying my invention, and Fig. 2 is an end view, partially in section and partially in elevation, of the interrupter shown in Fig. 1.

An inclosing housing 1 is provided with a 35 plurality of feet 2 extending laterally from its base for the purpose of facilitating the mounting of the same on the ceiling or beneath the floor of a railway vehicle. A cover member 3 is hinged to a portion of the 40 housing 1, and a plurality of internal lugs 4 are provided on the side opposite to the cover member 3 for supporting the interrupter mechanism.

A plate 5, constructed of insulating material, is secured by screws 6 to the lugs 4 and has mounted thereon a stationary terminal member 7, an electromagnet 8, a pivotally-mounted operating lever 9, a pivotally-mounted movable member 10, a latching device 11 and a calibrating device 12.

The operating lever 9 is pivotally mounted 45 on a post 13 upon which is also mounted the movable member 10 that has a contact-carrying member 14 pivotally connected

thereto. A stationary contact finger 15 is 55 secured to the stationary contact terminal member 7, and a contact finger 16 is secured to the contact-carrying member 14. A tension spring 17 is operatively connected between a stationary member 18 and the movable member 10, and a compression spring 19 is disposed between the contact-carrying member 14 and the movable member 10. 60 Similarly, a tension spring 20 is disposed between the lever arm 9 and the movable member 10. The movable member 10 is so constructed that, when the lever arm 9 is turned in a clockwise direction, it engages a portion 21 of the movable member 10, thereby moving the same to tension the 65 spring 17 and compress the spring 19. Thus, when the movable member 10 is actuated, the movable contact member 16 engages the stationary contact member 15, and, since the contact-carrying member 75 14 is pivotally mounted on the member 10, the contact member 16 will have a sliding motion with respect to its coöperating contact member 15.

The latching device 11 comprises a 80 spring-restrained member 22 of substantially a channel shape that is pivotally mounted on a pin 22^a near one end thereof. A portion near its other end is cut away to constitute an engaging or stop member 23 85 for the movable member 10. When the movable member 10 is moved to such position by the lever arm 9 that the contact members are in engagement, the member 22 will assume substantially the position shown 90 in the drawings.

The electromagnet 8 comprises a magnetizable core member 24, a pivotally-mounted armature 25 and a winding 26 one terminal of which is operatively connected to the 95 contact-carrying member 14 and the other terminal of which is connected to a conductor 27^a that is adapted to pass through a bushing 27 in the housing 1. A similar bushing 28 is provided for a conductor 29 that is connected to the stationary contact terminal 7. A magnetizable member 30, that is adapted to extend to a position adjacent the contact members 15 and 16, is mounted on the lower surface of the supporting plate 5 in engagement with the stationary core member 24 of the electromagnet 8. Similarly, a magnetizable member 31, that is adapted to ex-

tend from the armature 25 of the electromagnet 8 to a position adjacent the contact members 15 and 16, is mounted on the cover 3. Thus, a strong magnetic field is directed 5 across any arc that may be drawn when the contact members 15 and 16 are separated for the purpose of extinguishing the same.

A bell-crank lever 32 is operatively connected to the armature 25 of the electromagnet 8 and has, loosely disposed in one arm thereof, a screw-threaded member 33 having a pointer 34 thereon. A spring 35 is operatively connected, at one of its ends, to one end of the screw-threaded member 32 10 and, at its other end, to a stationary member 36. A nut 37 is adapted to engage the other end of the screw-threaded member 32 and the pointer 34 is adapted to coöperate with a scale 38 to indicate the tension of the 15 spring 35 and, consequently, the value of current necessary to traverse the winding 26 of the electromagnet 8 to cause its armature 25 to operate.

A lip or projecting member 39 is mounted 20 on the armature 25 and is adapted to engage one end of a rocking lever 40 that is mounted on projections or brackets 41 on the post 13. The end 42 of the lever 40 is adapted to engage the latching member 22 25 and is so shaped that, when it is actuated by the armature 25, it causes the member 22 to turn in a counter-clockwise direction for the purpose of releasing the movable member 10 and, consequently, the movable contact 30 member 16. A pin 43 is mounted on the operating lever arm 9 adjacent the member 22 and is adapted to move the member 22 in a counter-clockwise direction when the lever arm 9 is moved in a similar direction. Thus, 35 the interrupter may be tripped either automatically at a predetermined overload or manually by a relatively small movement of the operating lever arm 9.

A portion of the housing 1 is cut away to 40 permit the insertion of an arc chute 44 that may be constructed of asbestos or other insulating material. The arc chute 44 is adapted to surround the contact members 15 and 16 and is secured in position by a 45 slideable bolt or latch 45 that is locked by a screw 45^a which, with the latch, are accessible from the exterior of the housing 1. By such construction, the arc chute 44 may be removed from the housing 1 without the 50 necessity of opening the same.

When it is desired to manually trip the 55 interrupter, the lever arm 9 is moved a relatively short distance in a counter-clockwise direction to cause the spring 20 to be tensioned. When the spring 20 is sufficiently tensioned, the pin 43 will move the member 22 out of engagement with the movable member 10, and the spring 17 will quickly turn the movable member 10 about the post 60 13 and, in coöperation with the spring 19,

will cause the movable contact member 16 to quickly disengage the stationary contact member 15 with a desirable sliding motion.

When a sufficiently large overload traverses the device to cause the armature 25 to 65 operate against the action of the spring 35, the rocking lever 40 will be actuated to cause the movement of the member 22 in a counter-clockwise direction and the disengagement of the contact members 15 and 16, 70 substantially as hereinbefore set forth.

I do not limit my invention to the particular structure set forth, as it may be variously modified without departing from the spirit and scope of the invention as set 75 forth in the appended claims.

I claim as my invention:

1. In a circuit interrupter, the combination with a stationary contact member, of a pivotally-mounted member having a projection thereon, a movable contact member pivotally mounted on the pivotally-mounted member, an operating lever arm adapted to engage the projection on the pivotally-mounted member to actuate the movable 85 contact member, a latch adapted to engage the projection on the pivotally mounted member to hold the contact members in engagement, and means for tripping the latch. 90

2. In a circuit interrupter, the combination with a stationary contact member and a movable contact-carrying member having a projection thereon, of an operating lever arm adapted to engage the projection on the 100 movable member to actuate the same, a latch adapted to engage the projection on the movable member to hold the contact members in engagement, and means for actuating the latch member. 105

3. In a circuit interrupter, the combination with a stationary contact member and a movable contact-carrying member having a projection thereon, of an operating lever 110 arm adapted to engage the projection on the movable member to actuate the same, a latch adapted to engage the projection on the movable member to hold the contact members in engagement, means for yieldingly holding the operating lever arm in its closed 115 position, and means for actuating the latch member.

4. In a circuit interrupter, the combination with a stationary contact member and a movable contact-carrying member having 120 a projection thereon, of an operating lever arm adapted to engage the projection on the movable member to actuate the same, a latch adapted to engage the projection on the movable member to hold the contact members in engagement, and means for manually and automatically actuating the latch member. 125

5. The combination with a movable contact member and an operating lever rela- 130

tively movable with respect thereto, of a latch member for restraining the movable contact member in its closed position, a pivotally-mounted member having a beveled portion adapted to engage the latch member when it is actuated for the purpose of so moving the latch member as to release the movable contact member, and means mounted on the operating lever for also moving the latch member when the said operating lever is moved relatively to the contact member.

6. In a circuit interrupter, the combination with a stationary contact member, and

a movable contact-carrying member having 15 a projection thereon, of an operating lever arm adapted to engage the projection on the movable member to effect closure of the contact members, a latch for engaging the projection to hold the contact members in engagement, and a pin mounted on the operating lever arm for moving the latch out of engagement with the projection on the movable member.

In testimony whereof, I have hereunto 25 subscribed my name this 6th day of October, 1916.

HARRY R. MEYER.
